To all whom it may concern:

Be it known that we, HARRY KATTAU and EARL ROLOSON, citizens of the United States, and residents of Groton, in the county of Tompkins, and State of New York, have invented a new, original, and ornamental Design for a Detachable Top Plate for a Casing for a Typewriting Machine, of which the following is a specification, reference being had to the accompanying drawings forming a part hereof.

In the drawings, Fig. 1 is a perspective view of a detachable top plate for a casing for a typewriting machine, taken from the rear of the plate, showing our new design;

Fig. 2 is a top plan view of the plate; and

Fig. 3 is a side edge elevation of the plate, which plate is detachably applied to the machine casing at the rear of the keyboard of the machine to serve as a removable cover for the space within the casing which extends around the front and sides of the type basket at the rear of the keyboard of the machine.

The top plate is a complete article of manufacture.

We claim:

The ornamental design for a detachable top plate for a casing for a typewriting machine, as shown and described.
